UNITED STATES PATENT OFFICE.

CHARLES H. SCAMMELL, OF NEW YORK, N. Y., ASSIGNOR TO CHARLES H. SCAMMELL COMPANY, OF NEW YORK, N. Y., A CORPORATION OF NEW JERSEY.

WATERPROOFED LATHING.

Application filed March 13, 1922. Serial No. 543,134.

To all whom it may concern:

Be it known that I, CHARLES H. SCAMMELL, a citizen of the United States, residing at New York city, county of New York, and State of New York, have invented certain new and useful Improvements in Waterproofed Lathing, fully described and represented in the following specification and the accompanying drawings, forming a part 10 of the same.

The object of the present invention is to provide an improved waterproofed lathing, combining a waterproofed backing sheet and metal lath of any well known type, in 15 which the strands of the metal are so separated and shaped that with the backing sheet applied thereto there still will be sufficient space to permit plaster or other cementitious material applied to the lathing to be 20 firmly anchored thereto. Although the waterproofed lathing of the present invention will be found capable of various uses, it may be used with especial advantage in stucco work, and especially outside stucco work, 25 because the deteriorating effect of moisture on the wooden support for the stucco material, due to the moisture in such material when applied to the lathing or subsequent access of rain water effected by saturation. 30 of the more or less porous stucco material, is effectively prevented by the use of the present waterproofed lathing, and the life of the structure as a whole thereby prolonged. In addition, the invention provides 35 an article which greatly simplifies and expedites the formation of stucco on structures, because the waterproofed lathing of the present invention is supplied as a unitary article and may, therefore, be quickly secured to its support in one operation, while heretofore it has been the practice in stucco and similar work, to first secure tar paper to the boarding support, then secure the metal lathing thereto, and then apply the 40 stucco material. The use of such sheets, is objectionable, of course, not only because not fully waterproof but also because of the time required to apply such paper over that required for the use of the present invention. 45

In order that others skilled in the art may understand the invention, one preferred embodiment thereof will now be described in connection with the accompanying drawing

and the novel features of the invention 55 then to be pointed out in the claims.

In the drawings—

Figure 1 is a face view showing a portion of boarding with the improved waterproofed lathing thereon, and a portion of stucco material anchored to the lathing, all the parts being shown broken away, and

Figure 2 is a section on the line 2—2 of Fig. 1.

Referring now to Figure 1, the letter A 65 indicates the usual boarding, fastened to studs or uprights in the usual manner for supporting strips B of lathing of the type hereinafter referred to. Such strips may be secured to the boarding in any suitable manner, such, for instance, as by stapling to the boards at the adjoining edges of the metal lath, which preferably overlap. C indicates a portion of stucco material applied to the lathing. 75

In Figure 2 there is clearly shown the relative positions of the backing sheet, the waterproofing coating thereon, and the metal lath, with respect to the support for the whole and the stucco material thereon. 80 In this figure, the letter D indicates the backing sheet for the lath, which sheet may advantageously be heavy paper or other suitable material. Between the backing sheet D and the strands of the metal lathing B, 85 there is interposed a layer of waterproofing material E, this latter being pure asphalt, or a material having at least equivalent waterproofing qualities and characteristics which will permit it to be softened by heat, 90 so that the strands of the metal lathing B may be embedded therein to a sufficient extent to cause the backing sheet D to adhere to such lathing, as hereinafter explained. The metal lathing preferably used with the 95 present waterproofed backing, is of a type substantially like that shown and known as expanded metal, wherein the metal is slit and the strands drawn or forced out to open the slits and turn the strands at an angle to 100 the plane of the metal, so that when the waterproofed backing is adhesively or otherwise secured thereto secure anchorage for the stucco material will be afforded.

One method of forming the improved 105 waterproofed lathing above described, consists in taking asphalt, preferably 96% to 98% pure, and with a melting point of from

- 140° to 160° F., heating it sufficiently to soften it and then applying this to heavy paper in any convenient manner so as to coat the whole surface of the paper. Asphalt of this melting point is efficient and handles well even when cold. Ordinarily the coating of but one side of such paper will be sufficient, although both sides may be coated, if desired. Such waterproofed backing sheet is then applied to the strips of metal lathing while the asphalt thereon is still soft, so that the lathing is efficiently secured, whereupon the sheets may be rolled up into the usual lathing roll.
- 15 What is claimed is:
1. A new article of manufacture, comprising metal lathing formed to anchor plastic material between it and a plain surface in contact with such lathing, a backing sheet secured to said lathing, and a layer of water-

proofing material interposed between said backing sheet and lathing.

2. A new article of manufacture, comprising metal lathing formed to anchor plastic material between it and a plain surface in contact with such lathing, a backing sheet and an interposed layer of waterproof material adhesively securing said backing sheet and lathing together.

3. A new article of manufacture, comprising metal lathing formed to anchor plastic material between it and a plain surface in contact with such lathing, a backing sheet for said lathing, and an interposed layer of asphalt adhesively securing said backing sheet and lathing together.

In testimony whereof, I have hereunto set my hand.

CHARLES H. SCAMMELL.
